DESIGN FOR A TEXTILE FABRIC

Louis Bry, New York, N. Y.

Application March 20, 1939, Serial No. 83,690

Term of patent 3½ years

To all whom it may concern:

Be it known that I, Louis Bry, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein the figure is a plan view

of a piece of textile fabric showing my new design.

This design consists of diagonal rows of light vertical yarns and light double rows of yarns separated by rows of dark yarns, as shown.

I claim:

The ornamental design for a textile fabric, substantially as shown and described.

LOUIS BRY.
